UNITED STATES PATENT OFFICE.

JOHN W. BURDWIN, OF RAVENSWOOD, ILLINOIS.

HYDRAULIC VALVE.

SPECIFICATION forming part of Letters Patent No. 393,354, dated November 27, 1888.

Application filed May 13, 1887. Serial No. 238,117. (No model.)

To all whom it may concern:

Be it known that I, JOHN W. BURDWIN, a citizen of the United States, residing at Ravenswood, in the county of Cook and State of Illinois, have invented a new and useful Improvement in Hydraulic Valves, of which the following is a specification.

My invention relates to a duplex valve for controlling the supply of water under pressure to the operating-cylinder of a hydraulic elevator to produce the rising movement of the elevator car, cab, or platform, and the exhaust or discharge of water from said operating-cylinder to permit the descent of the car or cab.

15 The invention is also applicable for controlling the flow of liquids to and from other machines, comprising presses and rams which are operated by liquids under pressure.

The essential feature of my invention is the use of a valve or valves which are operated by the pressure of water or other liquids on a piston or pistons with which the said valve is combined, the pressure on the controlling-pistons being controlled by an auxiliary or pilot valve, which may be shifted directly and with small force by the operator in the elevator car or cab; and, further, by the admission of water or other liquids under pressure to act upon either side of said controlling-pistons, 30 and the release of the water which has acted upon the opposite side of said pistons, the auxiliary valve indirectly produces the movements of the main valves.

My invention consists in the novel construction and arrangement of the parts of my improved valve, which will be more fully hereinafter described, and pointed out in the claims.

To more fully illustrate the construction and operation of my improved valve, reference is made to the mechanism shown in the accompanying drawings, wherein like letters of reference indicate similar parts in the several views, and in which—

45 Figure 1 is a vertical section of the entire valve. Fig. 2 is a top plan view of the water-chest, auxiliary valve, and ports as it appears with the cover of the water-chest removed. Fig. 3 is a vertical sectional view of a modified form of a portion of my improved valve.

Referring to the drawings, it will be seen

that the valve is of the duplex pattern, composed of two cylinders, A and A', for the operating-valves B and B', which are in connection with pistons E and E', which are in turn controlled by the action of an auxiliary or pilot valve, F².

The cylinders A and A' are constructed with enlargements or belts H² H³ at the intersection of the inlet A² and outlet A³, and the said cylinders are further provided and fitted with a brass or other metallic lining, a², which is perforated, as at a³, in the whole area of the belt-space in the cylinders. The valves B and B' in the operating-cylinders A and A' are 65 constructed with water-passages a a running through them parallel with their travel, allowing the same water-pressure at each end of the valve and forming a balance thereby. Each plunger of these valves is made in three parts, 70 d, d', and d'', with leather or other suitable packing, d³, between the parts d and d', and also between the parts d' and d'', the several sections being held in place by the piston-rods H and H' from the controlling-pistons E and E', the said 75 ends passing through the valves and having shoulders d⁴ d⁴ at the top thereof and nuts d⁵ d⁵ resting against and confining the bottoms of said valves. The controlling-cylinders D and D' are arranged above the valve-chambers A 80 and A', and are separated therefrom by divisional heads e⁴ e⁴, which have glands e⁵ e⁵ in connection therewith surrounding the piston-rods H and H', said cylinders being constructed with ports e, e', e'', and e³, in a manner similar 85 to the cylinder of a steam-engine.

Above the controlling-cylinders, and forming the top heads, F, of the same, is a water-chest, F', having an auxiliary valve, F², seated therein, with which the ports e e' e'' e³, leading 90 to each end of the controlling-cylinders D and D', are in connection. The under side of the valve F² is formed with a chamber, G, which rides over the seat F³ and connects the several ports, as above described, and for the purposes well understood. This valve F² is connected to a valve-rod, F⁴, which projects outwardly from the valve through a suitable stuffing-box, f, and is connected with the elevator cab, car, or platform by suitable means and 95 operated therefrom. An exhaust-discharge pipe, G', is centrally connected to the seat F³, 100

as shown in Fig. 1, and projects outwardly from the top of the valve entire, as shown in Fig. 2. A pipe, G², Fig. 2, also connects with the water-chest F' and feeds water under pressure thereto from a suitable source.

The operating-valves B and B' are connected at their lower portions with a Y-connection, C, which unites the two valves at this point and forms only one water-passage, C², to the operating-cylinder of the elevator.

The operation of my improved hydraulic valve is as follows: When the auxiliary or pilot valve F² stands at the center of its stroke, as shown, the two ports e and e³ leading into the top portions of each of the controlling-cylinders D and D' are open and the two pistons E and E' are locked down by water-pressure and the operating-valves B and B' are closed. By moving the auxiliary valve F² to the right 20 the port e leading to the top of the cylinder D will be opened to the chamber G of the said valve F², and thence to the exhaust or discharge pipe G'. The same movement of the auxiliary valve F² to the right opens the port e³ leading to the bottom of the controlling-cylinder D, allowing the flow of water under 25 pressure below the piston E and forces the said piston to the top of the cylinder D, drawing the valve B upward, or opening the same and allowing the water from the main through branch A² and also through the Y-connection C at C² to flow into the operating-cylinder of the elevator, causing the rising motion of the elevator car or cab. Moving the valve F² 30 back to the center opens port e' from the bottom of cylinder D to the chamber G in the said valve F², and then to exhaust G' and port e to top portion of cylinder D, letting water under pressure run into the said cylinder D on top 35 of the piston E, forcing said piston down and closing valve B, and thereby stopping the rising movement of the elevator car or cab. Moving the auxiliary valve F² to the left opens port e³ from top portion of cylinder D' to the 40 exhaust G', through the chamber G and port e', to the bottom of cylinder D', opening the operating-valve B' and allowing the water in operating-cylinder of elevator to escape or discharge through the other branch of the Y-connection C, and through the outlet A³ of cylinder A' and allowing the elevator car or cab to descend.

It will be observed that only one operating-valve, B or B', is moved by one movement of the auxiliary or pilot valve F², the other remaining closed and held in a closed position by the pressure of water on its controlling-piston, thereby avoiding wear on the packing prevalent in this class of machines, where both 55 plungers of the operating-valve are attached to one valve-stem and the whole moved when the elevator car or cab is moved in either direction.

It will be understood that the whole combination of cylinders, pistons, and valves are 60 provided with necessary packing and glands

at the points there necessary to render the parts water-tight.

All of the movements of the valve are under the control of the operator in the car or cab of the elevator through the medium of the auxiliary valve and its connections.

It is obvious that slight variations might be made in the construction of the parts without departing from the nature and principle of my invention.

Having thus described my invention, I claim—

1. In a hydraulic valve, the combination of two vertically-arranged valve cylinders, a shell or casing for said cylinders having perforations therein, a single Y-connection uniting the lower portions of said valve-cylinders, the controlling-cylinders for the valve-cylinders, arranged immediately above the same, a single water-chest arranged on top of said controlling-cylinders, a valve-seat arranged within the said water-chest and having ports therein leading to the upper and lower part of the controlling-cylinders, and an exhaust pipe, G', in connection therewith, as set forth, and an auxiliary valve mounted upon said seat and operating in connection with the ports and exhaust-discharge therein, substantially as described.

2. In a hydraulic valve, the combination of the two valve-cylinders, the ingress and egress openings A² and A³, the hollow enlargements or belts H² and H³ surrounding the lower portions of said valve-cylinders, the one communicating with the ingress-opening and the other with the egress-opening, the shells or casings a² in the valve-cylinders having perforations a³ therein and forming seats for the divisional heads e⁴, the controlling-cylinders mounted on top of the valve-cylinders in a direct vertical line and separated therefrom by the divisional heads e⁴, valves and pistons working in said cylinders independently of each other, the water-chest, and an auxiliary or pilot valve in said chest, substantially as described.

3. In a duplex hydraulic valve, the duplex cylinders A A' and a single connecting-passage, C, the perforated plates a², covering the inlet and outlet, the enlargements or belts H³, provided in the valve-casing opposite the inlet and outlet, the perforated plates a², covering the belts or enlargements, the cylindrical valves B B', fitting the bore of the cylinders A A' and adapted to cover or uncover the inlet and outlet, the controlling-cylinders D D' above the cylinders A A', the pistons E E', fitted within the cylinders D D', the stems H H', connecting the pistons to the valves, and the auxiliary valve F² to control the admission of the water to the cylinders D D' to actuate the pistons, as set forth.

4. A duplex hydraulic valve, comprising the duplex valve-cylinders A A', the duplex controlling-cylinders D D', arranged above the same, the inlet A², the outlet A³, said inlet and

outlet having a single connecting passage, the valves B B', fitting the bore of the cylinders A A' and adapted to cover and uncover the inlet and outlet, the pistons E E' within the cylinders D D', the stems H H', connecting the pistons E E' to the valves B B', so that the latter will move simultaneously with the former, the single water-chest F' above the cylinders D D', the ports e e², connecting the water-chest to the top of the cylinders D D', the auxiliary valve F² within the water-chest, the ports e' e² leading from the water-chest down to the in-

ner end of the cylinders D D' at one side, said ports e' e² being covered and uncovered by the pistons E E', and the exhaust-port G', combined, arranged, and operating as set forth.

In testimony that I claim the foregoing as my own I have hereto affixed my signature in presence of two witnesses.

JOHN W. BURDWIN.
